BLOWER USING SLUGS OF GRANULAR MATERIAL TO CUT DEPOSITS FROM HEATING SURFACES

Ralph M. Hardgrove, North Canton, Ohio, assignor to The Babcock & Wilcox Company, New York, N. Y., a corporation of New Jersey

Application May 16, 1955, Serial No. 508,579

4 Claims. (Cl. 51—8)

This invention relates to apparatus for cleaning the gas contacted surfaces of tubular heat exchangers by projecting relatively hard pellets toward such surfaces to dislodge deposited solids therefrom, the pellets being pressure-fluid-borne to the projection zone. More particularly, the invention is directed to novel mechanism for conveying the pellets from a pellet supply means to the projection zone.

In one important class of tubular heat exchangers, heat transfer is effected by heated gases flowing over the exterior surfaces of metal tubes through which flow relatively cooler liquids or vapors. A typical example is a water tube steam boiler or vapor generator, in which heat from combustion gases flowing over the tubes is used to convert the liquid to vapor and frequently to superheat the vapor. The combustion gases may be further utilized to superheat vapor of a lower pressure, to preheat the combustion air, and to preheat the liquid entering the generator.

The heating gases are produced by the combustion of a suitable fuel, usually coal, gas, or fuel oil, in the presence of combustion supporting air. Depending upon the characteristics of the fuel and upon the combustion conditions, the resultant gaseous products of combustion flowing through the gas passes of the heat exchanger carry a certain amount of non-combustibles in suspension. A typical non-combustible customarily present is slag.

As the gases flow over the relatively cooler tubes, the non-combustibles tend to deposit on the tube surfaces. As these deposits build up, they correspondingly reduce the efficiency of heat transfer from the heating gases to the tubes and, if not removed, may eventually bridge inter-tube spaces and partially block the gas passes. Hence, it is desirable to remove these deposited non-combustibles either at intervals whose frequency is determined by the rate of growth of the deposits or at regular intervals.

One arrangement for removing these deposits from the tube surfaces involves projecting relatively hard pellets toward the tube surfaces to dislodge the deposited solids therefrom. As the pellets must strike the tube surfaces with considerable force to be effective, a convenient discharge arrangement comprises carrying the pellets to the projection point in a high velocity stream of fluid, such as air, under pressure. At the projection point or zone, suitable means are provided for directing pellets at high velocity in cleaning relation toward the tube surfaces.

The present invention is directed to mechanism for conveying a pressure-fluid-borne stream of pellets from a pellet supply to the pellet projection zone. This mechanism comprises a first conduit means, or air conveyor, extending from a point outside the heat exchanger into the pellet projecting and directing means. This conveyor is connected to a source of fluid under pressure. A second conduit means is connected to the first means at a point outwardly, or upstream, of the pellet projecting means and has a portion extending in telescoped, concentrically spaced relation through the first conduit means into the pellet projecting means. A pellet feeding means

2

is connected to this second conduit means downstream of such connection point, and preferably between such point and the telescoped portion, for feeding pellets into the pressure fluid stream confined by the second conduit means for pressure-fluid-borne delivery to the pellet projecting means.

In a preferred form of the invention, a pellet hopper is provided having a discharge trough extending along its bottom and in communication therewith. One end of this trough has a gravity connection to the second conduit means, and a conveyor, preferably of the screw type, extends along the trough to move the pellets to the discharge connection. This conveyor is driven by means mounted outside the hopper and having a driving connection, such as a shaft, extending through a bearing or stuffing box mounted externally of the trough. To maintain the pressure sealing of the hopper, a conduit is connected between the source of fluid under pressure and the stuffing box. Preferably, an equalizing connection is provided between the pellet discharge connection and the hopper space above the pellets.

For an understanding of the invention principles, reference is made to the following description of a typical embodiment of the invention as illustrated in the accompanying drawing. In the drawing:

Fig. 1 is a partial schematic and partial sectional view of tube cleaning apparatus embodying the invention as arranged in operative association with a portion of a tubular heat exchanger;

Fig. 2 is an enlarged side elevation view, partly in section, of the pellet feeding hopper and its connection to the pellet conveying means and associated components;

Fig. 3 is a transverse sectional view of the hopper on the line 3—3 of Fig. 2;

Fig. 4 is an axially sectional view of the bearing or stuffing box;

Fig. 5 is a sectional view on the line 5—5 of Fig. 2; and

Figs. 6 and 7 are, respectively, side and end elevation views of drive mechanism for reciprocating and rotating the pellet blowing tube, Fig. 6 being partly in section.

Referring to Figs. 1 through 4 of the drawings, the invention cleaning apparatus is illustrated as in operative relation with a tubular heat exchanger 10 comprising a side wall 11 along which extend wall protecting water tubes 12 and 13. While the water tubes are generally in uniformly spaced parallel relation along wall 11, a pair of tubes 13 are bent away from each other at a point along their length to define a port 14 in wall 11, which port may be referred to as a blower tube port. The portion of the heat exchanger 10 shown in Fig. 1 is comprised between side wall 11 and a tube-formed division wall 15 which may likewise comprise water tubes. In the gas pass defined by wall 11, tubes 12 and 13, and division wall 15, are disposed tubes 16 of a superheater, for example.

The gas flow over the superheater tubes is as indicated by the arrow, and the flowing gaseous products of combustion carry solids in suspension, such as slag particles, unburned fuel particles and fly ash, which solids tend to deposit upon the surfaces of the tubes 12, 13, 15 and 16, particularly the tubes 16. These deposits, if not checked, build up to the point where they may eventually bridge or close the spaces between adjacent tubes and thus obstruct the gas flow through the gas pass. In addition, the deposits on the tube surfaces decrease the efficiency of heat transfer from the heating gas to the tube walls. Consequently, it is important that these deposits be cleaned from the tubes at least periodically.

Fig. 1 illustrates schematically one type of cleaning arrangement which is effective in cleaning the tube sur-

faces of the accumulated deposits by projecting relatively hard pellets in-between, along, and against the tube surfaces. This apparatus includes a feed tank or hopper 20 having filler neck 22 whose outer end is closed by a removable closure 23 which may be removed to replenish the supply of pellets. The bottom wall 24 of tank or hopper 20 has a relatively narrow slot 26 leading to a trough or screw housing 27 which may comprise a cylindrical section. An agitator or feed screw 25 extends along trough 27, being rotatably mounted in bearings 28 and 29, the shaft of screw 25 extending outwardly through a pressure sealed stuffing box 31. The screw 25, which is of substantially less diameter than its housing 27, is rotated by an air motor 30 driving the screw through a belt and pulley drive 32.

Air for operating motor 30 is delivered to the motor through a conduit 33, controlled by a valve 39 and connected to a first conduit means, or main air line, 34 receiving air under pressure, from a suitable source, through a diaphragm operated valve 35. A conduit 36 is connected from main air line 34 to stuffing box 31 to provide a pressure seal at the point where the screw shaft emerges from the trough 27. Main air line 34 is connected at its discharge end through a valve 37 and a connection 38 to a main air tube 40 telescopcd within a blower tube 45 extending into port 14.

Upstream of valve 37, a conveying air line or second conduit means 41 is branched off from main air line 34 at a point 21 and has a portion extending in concentric spaced relation through the air tube 40 to a point in advance of the discharge end of the latter. Air line 41 is centrally supported in air tube 40 by means of radial lugs 44 welded to circumferentially spaced points on line 41 and slidably engaging tube 40. A gravity discharge connection 42 extends from the end of trough 27 or screw housing to air line 41, whereby pellets from tank 20 may be delivered into the stream of pressure air flowing along conveying air tube 41. A pressure equalizing connection 43 extends between the discharge end of trough 27 and the filler neck 22, so that the air pressures above the granular material charge in the tank 20 and in the trough 27 at the discharge end of screw 25 are equalized by the tubular connection 43.

Blower tube 45 is telescoped on tube 40 and is mounted for axial reciprocation and simultaneous rotation relative to port 14. Such reciprocation and rotation of tube 45 is provided by a suitable drive mechanism schematically illustrated at 50 and described more fully hereinafter. This drive mechanism, with the tube 45 rigidly attached thereto, is reciprocated axially of the air tube 40 and the pellet conveying air line 41. Tubes 40 and 41 are rigidly secured together as indicated in Fig. 2. The limit of reciprocation is defined by the solid line and the dot and dash line positions of tube 45 as shown in Fig. 1 at 45'.

The reciprocating and tube rotating mechanism 50 comprises a carriage 90 having support wheels 91 engaging the flange 92 of a beam 93 extending parallel to and above tube 45. Driving wheels 94 on the carriage mesh with a rack 95 along the undersurface of flange 92. An air motor 96 on carriage 90 drives wheels 94.

Tube 45 is secured to a sleeve assembly 97 rotatable on bearings 98 in carriage 90 and having fixed thereto a driving gear 99 rotated by driving connections (not shown) to motor 96. The free end of tube 45 is supported on bearings 101 in a hanger 100 secured to the end of beam 93 nearest the heat exchanger. Suitable controls are provided for effecting automatic reciprocation of carriage 90 along beam 93.

In operation, the rotating screw 25 delivers pellets from tank 20 along screw housing 27 to "drop" connection 42 and thence into conveyor air line 41. The pellets delivered through the conveyor air line 41 and discharged from the outer end thereof are carried along by the high pressure air flowing through the air tube 40 embracing

conveyor air line 41. Valve 37 controls the air flow between pipes 40 and 45. The fluid-borne pellets are thus carried to a suitable discharge nozzle arrangement at the outer end of blower tube 45. This discharge arrangement, which forms no part of the present invention, comprises a pair of oppositely radially directed nozzles 46 adjacent the closed outer end of tube 45.

Referring more particularly to Figs. 2, 3 and 4, the filler neck 22 is welded into an annular upper end plate 47 welded to the hopper side wall 48. The hopper has a converging bottom formed by sloping side plates 51 welded to side walls 48 and to screw housing 27. Flow restrictors or equalizers 52 extend through and interconnect sloping walls 51.

15 A cup-shaped member 53 fits over and closes one end of screw housing 27 and supports the sleeve bearing 28 for one end of screw conveyor 25. The latter has a driving shaft 55 extending through an annular end plate 56 (Fig. 4) welded into the opposite end of trough 27. This shaft extends through the stuffing box or bearing 31 and into the second bearing 29 mounted on an angular bracket 57 on supporting framework 58. Framework 58 also supports the air motor 30 having a driving pulley 61 connected by belt 32 to a driven pulley 62 on shaft 55. The air supply for motor 30 is provided by an air line 63 connected to conduit 34 downstream of valve 35 and having its opposite end connected to a centrifugal moisture separating chamber 65. Conduit 33 interconnects chamber 65 and motor 30 through valve 39.

20 30 The bearing or stuffing box 31 includes a sleeve 66 welded to plate 56 and having studs 67 welded thereto and extending longitudinally therefrom. These studs receive nuts 68 which force a packing flange 70 inwardly through sleeve 66 to compress packing 71 against a ring 75 which in turn presses packing 72 against end plate 56. The ring 75 has a circumferential channel 76 which is in communication with a port 77 in sleeve 66. Air from line 33 is delivered to port 77 through a threaded nipple 78, flows into channel 76, and thence through 25 ports 79 to shaft 55. This maintains a pressure seal preventing loss of pressure from the conduit and trough.

The discharge connection 42 is connected to a T fitting 80 interposed in second conduit means 41 and having its end opposite connection 42 closed by an access plug 81.

25 35 While a specific embodiment of the invention has been shown and described in detail to illustrate the application of certain principles, the invention may be embodied otherwise without departing from such principles.

40 45 What is claimed is:

1. In combination with means constructed to project relatively hard pellets to dislodge deposited solids from the exterior tube surfaces of a heat exchanger tube bank contacted by gases carrying solids in suspension which deposit on such surfaces; mechanism for conveying a high velocity stream of such pellets to such pellet projecting means comprising, in combination, first conduit means extending into the pellet projecting means from a point spaced from the latter; means for connecting a source of fluid under pressure to the outer end of said first conduit means for delivery of fluid at high velocity to the pellet projecting means; second conduit means connected to said first conduit means at a point spaced from such pellet projecting means and extending into said first conduit means; a pressure sealable hopper arranged to receive a supply of the pellets; a conveyor housing extending along the bottom of said hopper and in communication therewith; a gravity discharge connection interconnecting one end of said housing and said second conduit means downstream of said point for feeding of pellets into the high velocity pressure fluid stream confined by said second conduit means for high velocity delivery of pellets to such pellet projecting means; a conveyor extending along said housing to move the pellets to said discharge connection; conveyor driving means mounted outside said hopper and housing; a driving connection between said

driving means and said conveyor extending through a bearing mounted externally of said housing; and a pressure connection extending between said first conduit means and said bearing.

2. In combination with means constructed to project relatively hard pellets to dislodge deposited solids from the exterior tube surfaces of a heat exchanger tube bank contacted by gases carrying solids in suspension which deposit on such surfaces; mechanism for conveying a high velocity stream of such pellets to such pellet projecting means comprising, in combination, first conduit means extending into the pellet projecting means from a point spaced from the latter; means for connecting a source of fluid under pressure to the outer end of said first conduit means for delivery of fluid at high velocity to the pellet projecting means; second conduit means connected to said first conduit means at a point spaced from such pellet projecting means and extending into said first conduit means; a pressure sealable hopper arranged to receive a supply of the pellets; a screw housing extending along the bottom of said hopper and in communication therewith; a gravity discharge connection interconnecting one end of said housing and said second conduit means downstream of said point for feeding of pellets into the high velocity pressure fluid stream confined by said second conduit means for high velocity delivery of pellets to such pellet projecting means; a screw conveyor extending along said housing to move the pellets to said discharge connection; conveyor driving means mounted outside said hopper and housing; a driving shaft connecting said driving means and said conveyor extending through a bearing mounted externally of said housing; and a pressure connection extending between said first conduit means and said bearing.

3. In combination with means constructed to project relatively hard pellets to dislodge deposited solids from the exterior tube surfaces of a heat exchanger tube bank contacted by gases carrying solids in suspension which deposit on such surfaces; mechanism for conveying a high velocity stream of such pellets to such pellet projecting means comprising, in combination, first conduit means extending into the pellet projecting means from a point spaced from the latter; means for connecting a source of fluid under pressure to the outer end of said first conduit means for delivery of fluid at high velocity to the pellet projecting means; second conduit means connected to said first conduit means at a point spaced from such pellet projecting means and having a portion extending into said first conduit means; a pressure sealable hopper arranged to receive a supply of the pellets; a conveyor housing extending along the bottom of said hopper and in communication therewith; a gravity discharge connection interconnecting one end of said housing and said

second conduit means between said point and said portion for feeding of pellets into the high velocity pressure fluid stream confined by said second conduit means for high velocity delivery of pellets to such pellet projecting means; a conveyor extending along said housing to move the pellets to said discharge connection; conveyor driving means mounted outside said hopper and housing; a driving connection between said driving means and said conveyor extending through a bearing mounted externally of said housing; and a pressure connection extending between said first conduit means and said bearing.

4. In combination with means constructed to project relatively hard pellets to dislodge deposited solids from the exterior tube surfaces of a heat exchanger tube bank contacted by gases carrying solids in suspension which deposit on such surfaces; mechanism for conveying a high velocity stream of such pellets to such pellet projecting means comprising, in combination, first conduit means extending into the pellet projecting means from a point spaced from the latter; means for connecting a source of fluid under pressure to the outer end of said first conduit means for delivery of fluid at high velocity to the pellet projecting means; second conduit means connected to said first conduit means at a point spaced from such pellet projecting means and having a portion extending into said first conduit means; a pressure sealable hopper arranged to receive a supply of the pellets; a screw housing extending along the bottom of said hopper and in communication therewith; a gravity discharge connection interconnecting one end of said housing and said second conduit means between said point and said portion for feeding of pellets into the high velocity pressure fluid stream confined by said second conduit means for high velocity delivery of pellets to such pellet projecting means; a screw conveyor extending along said housing to move the pellets to said discharge connection; conveyor driving means mounted outside said hopper and housing; a driving shaft connecting said driving means and said conveyor extending through a bearing mounted externally of said housing; and a pressure connection extending between said first conduit means and said bearing.
